UNITED STATES PATENT OFFICE

167,613

PORTABLE RADIO CABINET

Robert D. Budlong, Skokie, Ill., assignor to Zenith
Radio Corporation, a corporation of Illinois

Application April 22, 1952, Serial No. 19,434

Term of patent 7 years

(Cl. D56—4)

To all whom it may concern:

Be it known that I, Robert D. Budlong, a citizen of the United States, residing at Skokie, in the county of Cook, State of Illinois, have invented a new, original, and ornamental Design for a Portable Radio Cabinet, of which the following is a specification, reference being made to the accompanying drawing, forming a part thereof.

Figure 1 is a perspective view of a portable radio cabinet with the handle in an upright position, showing my new design;

Figure 2 is a top view of the portable radio cabinet with the handle in lowered position.

The design of the side of the cabinet not shown is similar to the design of the side shown. The design of the rear portion of the cabinet, not shown, is plain.

I claim:

The ornamental design for a portable radio cabinet, as shown and described.

ROBERT D. BUDLONG.
